UNITED STATES PATENT OFFICE.

JESSE ALEXANDER, OF NEW YORK, N. Y.

TYPE-WRITING-MACHINE KEY AND TYPE-BAR ACTION.

1,203,837.

Specification of Letters Patent.

Patented Nov. 7, 1916.

Original application filed May 22, 1912, Serial No. 698,879; renewed March 18, 1915, Serial No. 15,388; again renewed October 22, 1915, Serial No. 57,382. Divided and this application filed March 20, 1915, Serial No. 15,756.

To all whom it may concern:

Be it known that I, JESSE ALEXANDER, a citizen of the United States of America, and residing at New York, in the county of 5 Kings and State of New York, have invented new and useful Improvements in Type-Writing-Machine Keys and Type-Bar Actions, of which the following is a specification.

10 The main objects of the present invention are to provide a typewriter action of simple, sturdy and compact construction, having a light, quick touch and which will be capable of heavy manifolding work as well as the 15 usual lighter grade of typewriter work. In carrying out these objects I provide a double connection between each key lever and type bar, consisting of a link having a shoulder engaging the type bar at a point considerably forward of the pivot thereof at commencement of the printing stroke and having also a lost-motion connection with the type bar located at a point nearer to the pivot. The effect of these connections is to 20 start the type bar with an easy, light touch and then as the lost-motion is taken up to carry the type bar forward to printing contact with a quick sharp blow.

Another feature of the invention is the 25 mounting of the type bar segment and the bearing for the key levers in brackets which are secured to the inner sides of the side members of the supporting frame, whereby all of said members are maintained always 30 in proper relation.

Other features are the mounting of the key levers on four parallel shafts and the pivoting of the shanks of certain of the keys to their respective levers and guiding them 35 so that they will be compact and yet have a substantially true up and down vertical movement and will not interfere with each other.

Various other features will appear as the 40 specification proceeds.

In the accompanying drawings I have 45 illustrated a practical and preferred embodiment of my invention but I would have it understood that various changes and 50 modifications may be made without departure from the true spirit and scope of the invention. It will also be understood that the terms employed herein are terms of description rather than of limitation except 55 as may be required by the prior art.

Figure 1, is a vertical, substantially central, sectional view of a machine embodying the invention. Fig. 2, is a perspective partly broken view of the key and type bar mechanism and one of the supporting 60 brackets removed from the main supporting frame. Fig. 3, is a vertical section and rear view of the machine taken on a plane at right angles to that of Fig. 1. Fig. 4, is a detail view showing one of the upper bank 65 of key levers depressed and the type bar connected therewith in printing position. Figs. 5, 6 and 7 are detached views of key levers from the lower, the second and the third bank of key levers.

15 designates the main supporting frame of suitable construction, preferably that shown in my application Serial No. 698,879, filed May 22nd, 1912, of which the present case is a division. Secured to the inner 70 faces of the side members of this frame by means of rivets, screws 16, or like fastenings, are the oppositely disposed supporting brackets 17, which constitute mountings for the type bar segment and key lever supports. 75 These brackets are accordingly provided with inwardly extending supporting ledges 18 at their upper rearward portions for the support of the type bar segment and with sockets 19 in their lower forward portions 80 for the type lever supporting shafts.

20 designates the type bar segment, provided with lugs 21 at the ends thereof resting on the supporting ledges of the bracket and suitably secured in such position as by 85 means of screws 22. The type bars 25 are pivoted on the pivot wire 26 carried by the segment and their forward free ends normally rest in the type basket 27. The operating keys are in the present disclosure 90 arranged in four rows or banks and the key levers of the different banks are pivoted on four different centers disposed so as to substantially compensate for the difference in 95 length of the several sets of key levers.

100 30 designates a key lever of the lower or first bank pivoted at 31 on the forward pivot rod 32.

33 is a key lever of the second bank, pivoted at 34 on the pivot rod 35, in rear of 105 the first pivot rod.

36 is a key lever of the third bank pivoted at 37 on the third pivot rod 38, and 39 is a key lever of the upper or fourth bank pivoted at 40 on the fourth and rearmost pivot 110

rod 41. These pivot rods and the carriage shift rod 28 may be removably held in their bearings in the supporting brackets by means of the detachable cap pieces 29, one of which is shown in Fig. 2.

The keys 42 and 43 of the lower and second banks are shown connected directly to their respective levers and the keys 44 and 45 of the two upper banks are shown carried by shanks 46 and 47 which are pivoted to their levers by pivot joints 48 and 49. These pivoted key shanks are guided for substantially vertical up and down movements by transversely extending guide bars 50 and 51 notched at 52 to receive the shanks, which are slotted at 53 to fit over such bars. The guide bars are supported at their ends by brackets 54 secured inside the side plates of the frame. These brackets may be adjustably secured in place as by means of screws 55 engaged in enlarged openings 56 in the brackets so as to permit of the guide strips being set to properly guide the shank portions of the divided key levers. At the center the guide bars are shown connected together in proper spaced relation by a bar 57 which is adjustably secured by a screw 58 to a forwardly projecting bracket 59 carried by the transversely extending intermediate plate or portion 60 of the frame.

The key levers are connected with the type bars by means of push links 65 pivoted to the rear ends of the key levers at 66 and having both a temporary long-leverage connection with the type bars for starting them on their printing stroke and a short-lever lost-motion connection for carrying the type bars, once started, to their full printing position. The links are accordingly each provided with a forwardly extending fork or arm 67 terminating in a shoulder 68 normally engaging the lower edge of the type bar at a point lower than and considerably in advance of the type bar pivot and they have a pin and slot connection 69 with the type bar at a point forward of but closer to the pivot. The pin is, as shown, usually carried by the type bar and the slot is formed in the upper end of the link.

In operation, when a key is depressed, the rear end of the key lever is elevated. The forwardly located shoulder on the push link mounted on the rear end of such lever being then in engagement with the lower edge of the type bar, the type bar is started on its printing stroke, the leverage exerted at this point being sufficient to start the type bar with an easy quick movement. As the type bar travels upward the lost-motion in the pin and slot connection is taken up and the type bar is then carried the balance of its stroke by the link acting on the pin. This transfer of the driving force to a point closer to the type bar pivot accelerates the speed of the type bar, thus adding to the force of the

blow and increasing the speed of action. The type bar may be provided with a stop shoulder 70 on its upper edge for engagement with a stop surface 71 on the face of the type bar segment to limit the printing stroke and cause the type bar to rebound to start the return stroke. The return stroke may be further assisted by a spring pressed rod 74 disposed above the rearward portions of the key levers and serving to cushion such levers and impart an initial reverse movement to them. At the printing point the type bar may be guided by spaced apart rolls 72 providing a guide passage for the flange 73 of the type bar.

The carriage, ribbon feed and escapement mechanism may be of any suitable construction such as that disclosed in the parent application Serial No. 698,879 above referred to. In this case the carriage is indicated at 75 carrying the platen 76 and traveling on front and rear guides 77, 78. The ribbon 80 is carried by spools 81 and is fed from side to side by reciprocating pawls 82 (only one shown) which engage ratchet wheels 83 on the lower ends of the ribbon spool shafts 84. At the printing point the ribbon is guided and lifted into printing position by a ribbon lift 85 which is connected at its lower end to the arm 86 of a rock shaft 87 which is operated from the universal bar.

The universal bar is designated 90 and is shown guided in a slot 91 in the back of the type bar segment in position to be engaged and operated by projections 92 on the upper edges of the type bars, as indicated in Fig. 4. At the rear the universal bar is supported by being pivoted at 93 to a rocker 94 which is pivotally supported at 95. On the rear edge of the universal bar is a hook 96 engaging in a slot 97 in the upstanding arm 98 on shaft 99, this arm being connected by a link 100 with the arm 101 of the rock shaft 87. A spring 102 draws the universal bar forward returning it to position after being engaged and operated by the key levers. The universal bar thus yielding supported also cushions the type bars and helps return them to the position of rest. The universal bar operates the escapement and through the connections described also operates the ribbon lift.

From the foregoing it will be apparent that the invention provides a machine which is of very simple, strong and compact construction, possesses a light, quick action and is capable of heavy manifolding as well as lighter work. The special mounting of the parts and the action in supporting brackets insures the maintenance of the proper relation between such parts and the pivotal mounting and guidance of the shanks of the key levers produces a substantially true up and down key movement and prevents interference between the several banks of keys.

What I claim is:—

1. In a key and type bar action, a pivoted type bar, a key lever pivoted at a point intermediate its ends, a push link pivotally connected at its lower end to the rear end of the key lever, said link having a lost-motion connection at its upper end with the type bar at a point forward of the pivot thereof and a temporary connection with said type bar at a point forward of said lost-motion connection at commencement of the printing stroke. 5
2. In a key and type bar action, a pivoted type bar, a pivoted key lever, a link pivotally connected with said key lever at its lower end and having a lost-motion connection at its upper end with the type bar at a point forward of the pivot of said type bar and a shoulder on the link in front of said lost-motion connection engaging the type bar at a point forward of the lost-motion connection for starting the type bar on its printing stroke. 10
3. A key and type bar action comprising a pivoted lever, a finger key connected to the forward end of said lever, a pivoted type bar, a link pivotally connected to the rear end of said lever and having a pin and slot connection with said type bar below 15 and in front of its pivot, and having a shoulder below and in front of said pin and slot connection for engaging said type bar to start its movement. 20
4. In a typewriter, a main supporting frame, brackets secured to the inner sides of the side members of said frame having inwardly extending lugs at the upper rearward portions thereof and shaft supporting portions forward thereof, a type bar segment supported on said inwardly extending lugs at the upper portions of said brackets, type bars pivoted in said segment, shafts supported between the forward shaft supporting portions of the brackets, key levers 25 pivotally supported by said shafts and links connecting said key levers and the type bars. 40
5. Key and type bar mechanism, comprising four parallel shafts, two banks of key levers pivotally supported by two of said shafts, two sets of levers pivotally supported 30
- by the other two of said shafts, vertically movable keys pivotally connected to said two sets of levers, guide rods for said vertically movable keys, pivoted type bars and links connecting said levers and said type bars. 55
6. In a typewriter, a main supporting frame, brackets secured to the inner sides of the side members of said frame, a type bar segment supported between the upper portions of said brackets, type bars pivoted in said segment, four parallel shafts supported between the forward portions of the brackets, two banks of key levers pivotally supported by two of said shafts, two sets of levers pivotally supported by the other two of said shafts, vertically movable keys pivotally connected to said two sets of levers, guide rods for said vertically movable keys, and links connecting the levers and 60 type bars. 65
7. In a typewriter, pivoted type bars, pivoted key levers connected therewith, guide bars adjustable in a plane toward and away from the type bars, and key shanks pivoted to the key levers and guided by said guide bars, the adjustment of said guide bars toward and away from the type bars enabling the guiding of the key shanks for moving in substantially a vertical plane. 75
8. In a typewriter, pivoted type bars, pivoted key levers connected therewith, guide bars having notched edges and key shanks pivoted to the key levers, longitudinally slotted to slide over the guide bars and having their edge portions guided in the notches in the edges of the guide bars. 80
9. In a key and type bar action, a pivoted type bar, a key lever pivoted at a point intermediate its ends, a push link pivotally connected at its lower end to the near end of the key lever, said link having a lost motion connection at its upper end with the type bar at a point forward of the type bar pivot, and a shoulder on the link extending forwardly beneath the type bar to engage said type bar at a point forward of the lost motion connection for starting the type bar on its printing stroke. 90
- 95

JESSE ALEXANDER.
